LIQUID SAMPLING APPARATUS

Edward Richard Harrington, Long Beach, Calif.

Application July 6, 1950, Serial No. 172,260

4 Claims. (Cl. 73—425.4)

1

The present invention relates generally to the sampling of liquids disposed in a large container, and more particularly to apparatus which may be lowered into a container so as to extract a sample of the liquid therein.

It is common practice, especially in the oil industry to find a so-called "average sample" of liquids disposed in a large container by first lowering an empty receptacle to the bottom of the container, then raising it to the surface. As is well-known to those versed in the art, this procedure is not always a positive method of obtaining a true indication of the character of the liquid or liquids in the containers. Since the receptacle has an inlet of fixed area, the rate at which liquid will enter it will depend upon the rate of speed at which the receptacle is moved. Ordinarily this rate of speed becomes a matter of guess work, and consequently much time may be lost by either moving the receptacle at too great a rate of speed whereby the receptacle must be again lowered and raised, or at too low a rate of speed whereby the receptacle is completely filled before it has traversed the depth of the container and must be emptied and again lowered and raised.

It is a major object of the present invention to provide liquid sampling apparatus which is adapted to obtain a true average sample of the liquid in a container. This object is primarily obtained by regulating the flow of liquid into a sample-taking receptacle by adjustably varying the area of the inlet to the receptacle.

A further object of this invention is to provide liquid sampling apparatus which includes a sample-taking receptacle having an air vent which may be adjusted as to area to thereby aid in regulating the flow of liquid into the receptacle and to limit the quantity taken as a sample.

It is another object of the present invention to provide liquid sampling apparatus which is sturdy of construction and foolproof in operation.

Other objects and advantages of the present invention will be apparent from the following detailed description of a preferred embodiment thereof, taken in conjunction with the following drawing, wherein:

Figure 1 is a side elevational view of the liquid sampling apparatus of the present invention;

Figure 2 is a central longitudinal sectional view taken on line 2—2 of Figure 1;

Figure 3 is a top plan view taken along line 3—3 of Figure 1;

Figure 4 is a horizontal sectional view taken on line 4—4 of Figure 1;

2

Figure 5 is a horizontal sectional view taken on line 5—5 of Figure 1;

Figure 6 is a reduced top plan view showing the liquid sampling apparatus of Figures 1 through 5 mounted within a sample-receiving receptacle;

Figure 7 is a reduced side elevational view of the apparatus and receptacle shown in Figure 6.

Referring to the drawings, there is shown in Figures 1 through 5 a novel liquid sampling apparatus which may be utilized in conjunction with an open-topped sample receptacle, such as shown in Figures 6 and 7. This apparatus broadly comprises a tube 1 which depends vertically from a cap 2, which cap is securable upon the open top of the receptacle, and includes an air vent 5 through which air originally contained in the receptacle may be displaced as the liquid sample enters thereinto.

In practice, the receptacle 4 may consist of a bottle formed with an externally threaded top. The cap 2 may be formed with internal threads and includes a resilient gasket 3 whereby a fluid-tight seal may exist between the cap and the bottle.

The upper end of the air vent 5 may receive a removable nozzle 6 whereby the rate at which the air may escape from the bottle may be controlled. Generally, the more viscous the liquid being sampled, the larger the orifice required. Where very viscous liquids are to be sampled the nozzle 6 may be removed completely. It is contemplated that the nozzle be retainable within the upper end of the air vent solely by friction.

In order that the tube 1 may be utilized with bottles of varying height, it may be threaded at its lower end so as to receive a sleeve 7 adapted to accommodate its length to that required for a particular bottle. The bottom of this sleeve 7 may also be threaded to receive a closure element 8 formed with a pair of openings in its side walls. A sleeve member 9 may be rotatably mounted upon the closure element 8, which sleeve member may be formed with a pair of apertures. These apertures may be brought into any desired degree of registry with the openings of the closure element 8 so as to control the rate of entry of the liquid to be sampled into the bottle. In Figure 2, the apertures are shown in full registry with the openings whereby the liquid may enter the bottle as indicated by the arrows.

Preferably, means will be provided for selectively locking the sleeve member 9 against rotation with respect to the closure element 8. For this purpose the base 10 of the sleeve member 9 may be secured to the closure element 8.

by means of a set screw 11. By this arrangement, once the sleeve member 9 is disposed at the desired position, the set screw 11 may be tightened.

In operation the cap 2 and its depending tube 1 will be screwed upon the top of the bottle 4. The bottle will then be lowered into a liquid to be sampled. The rate of entry of liquid into the bottle may be closely controlled by varying the degree of registry of the apertures of the sleeve member 9 with the openings of the closure element 8. This rate of entry may also be varied by the proper selection of nozzle 6 inserted in the upper end of the air vent 5.

It will be noted that the lower end of vent tube 5 is disposed downwardly some distance from the upper edge of tube 1. This distance is of paramount importance in that it limits the quantity of fluid taken into the sample bottle. Fluid will flow into the sample bottle at a rate determined by the size of the openings in the closure element 8, as well as the size of the aperture in nozzle 6 through which air in the bottle must escape. However, when fluid taken into the bottle rises to such a height as to obstruct the lower opening in vent tube 5, no further fluid can enter the bottle at or above the level in the tank being sampled. No further fluid can enter the sample bottle after the lower entrance to vent tube 5 is obstructed due to the inability of air left in the bottle to escape therefrom. Consequently this air serves as a cushion to prevent further entry of fluid. It will be apparent that by lowering the bottle below the depth at which the final seal to vent tube 5 is effected, additional fluid may flow into the bottle due to the increased hydrostatic head on the air remaining in the bottle. However, as the bottle is raised from the tank, the air remaining therein will expand in direct ratio to the pressure existing at the time the lower entrance to vent tube 5 was sealed. As this expansion of the air cushion occurs surplus liquid in the bottle will be forced upwardly through tube 1 to be discharged through the upper open end thereof.

The flow of fluid into the sample bottle after the fluid seal has been made is of no practical significance, as ordinarily the time required for the sample bottle to fill to the lower entrance to vent tube 5 is known, and the sample is taken accordingly.

It will be apparent to those skilled in the art that various modifications and changes may be made with respect to the aforescribed apparatus without departing from the spirit of the invention or the scope of the appended claims.

I claim:

1. Liquid sampling apparatus for use with an open top sample receptacle, comprising: a cap securable upon the top of said receptacle; a vertical tube depending from said cap, said tube being formed with an inlet at its upper portion and an outlet at its lower end and having an opening formed in its side wall at its lower portion; a coaxial sleeve member rotatably mounted upon the lower end of said tube, a side wall of said sleeve member being formed with an aperture which may be brought into a desired degree of registry with said opening by rotation of said sleeve member; and an air vent formed at the upper portion of said tube.

2. Liquid sampling apparatus for use with an

open top sample receptacle, comprising: a cap securable upon the top of said receptacle; a vertical tube depending from said cap, said tube being formed with an inlet at its upper portion and an outlet at its lower end and having an opening formed in its side wall at its lower portion; a coaxial sleeve member rotatably mounted upon the lower end of said tube, a side wall of said sleeve member being formed with an aperture which may be brought into a desired degree of registry with said opening by rotation of said sleeve member; an air vent formed at the upper portion of said tube; and a nozzle detachably mounted in the upper end of said air vent for controlling the rate of escape of said air.

3. Liquid sampling apparatus for use with an open top sample receptacle, comprising: a cap securable upon the top of said receptacle; a vertical tube depending from said cap, said tube being formed with an inlet at its upper end and having an opening formed in its side wall at its lower portion; a sleeve coaxially carried by the lower end of said tube and adapted for rotation about the longitudinal axis of said tube, a side wall of said sleeve being formed with an aperture which may be brought into a desired degree of registry with said opening upon rotation of said sleeve so as to vary the rate of entry of liquid to be sampled into said receptacle; a set screw carried by the lower end of said tube for selectively restraining said sleeve against rotation; an air vent formed in the upper portion of said tube permitting escape of air originally contained in said receptacle as said liquid enters said receptacle; and a nozzle detachably mounted in the upper end of said air vent for controlling the rate of escape of said air.

4. Liquid sampling apparatus for use with a sample receptacle having a threaded open top, comprising: a cap threadable upon the top of said receptacle; a gasket carried by said cap whereby it may sealingly engage the top of said receptacle; a vertical tube depending from the under side of said cap, said tube having an inlet at its upper end and an opening in its side wall at its lower portion; a sleeve coaxially carried by the lower end of said tube and adapted for rotation about the longitudinal axis of said tube, a side wall of said sleeve being formed with an aperture which may be brought into a desired degree of registry with said opening upon rotation of said sleeve so as to vary the rate of entry of liquid to be sampled into said receptacle; a set screw carried by the lower end of said tube for selectively restraining said sleeve against rotation; an elongate downwardly extending air vent formed in the upper portion of said tube permitting escape of air originally contained in said receptacle as said liquid enters said receptacle with the position of the lower inlet to said vent regulating the vertical height to which liquid may rise in said bottle; and a nozzle detachably mounted in the upper end of said air vent for controlling the rate of escape of said air.

EDWARD RICHARD HARRINGTON.
